DESIGN FOR A DESK

Russell B. Lindgren, Piedmont, and Chester H. Ristenpart, San Francisco, Calif.; said Lindgren assignor to said Ristenpart

Application November 18, 1944, Serial No. 116,429

Term of patent 14 years

(Cl. 33—7)

To all whom it may concern:

Be it known that we, Russell B. Lindgren and Chester H. Ristenpart, citizens of the United States of America and residing at Piedmont, county of Alameda, and State of California, and the city and county of San Francisco, and State of California, respectively, have invented a new, original, and ornamental Design for a Desk, of which the following is a specification, reference being had to the accompanying drawings forming part thereof.

Fig. 1 is a perspective view of a desk showing the design.

Fig. 2 is a bottom plan view of the desk of Fig. 1.

Fig. 3 is a perspective view showing the rear side of the desk of Fig. 1.

We claim:

The ornamental design for a desk, as shown.

RUSSELL B. LINDGREN.

CHESTER H. RISTENPART.
